UNITED STATES PATENT OFFICE.

EDWARD J. SHEEHAN, OF NEW YORK, N. Y., ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,272,543.

Specification of Letters Patent. Patented July 16, 1918.

Application filed June 12, 1914. Serial No. 844,602.

To all whom it may concern:

Be it known that I, EDWARD J. SHEEHAN, a citizen of the United States, residing at New York, in the county of New York and State of New York, have invented certain new and useful Improvements in Type-Writing Machines, of which the following is a full, clear, and exact description, such as will enable others skilled in the art to 10 which it appertains to make and use the same.

This invention relates to typewriting machines, and with regard to certain more specific features thereof, to paragraph key 15 mechanism.

One of the objects of the present invention is to provide a simple and practical mechanism adapted to permit the operator to regularly indent each paragraph on the 20 return movement of the carriage to line commencing position. Another object is to provide a mechanism of the above character having few parts which will be inexpensive to manufacture and install. A further object is to provide mechanism of the 25 first above-mentioned character which will be efficient in use and reliable in operation. Other objects will be in part obvious and in part pointed out hereinafter.

The invention accordingly consists in the 30 features of construction, combination of elements and arrangement of parts which will be exemplified in the construction herein-after set forth, and the scope of the application of which will be indicated in the 35 following claims.

In the accompanying drawings, wherein is shown one of various possible embodiments of this invention,—

Figure 1 is a side elevation partly in section of such parts of a typewriting machine as are necessary to obtain a clear understanding of the present invention;

Fig. 2 is a plan view of certain parts 45 shown in Fig. 1; and

Fig. 3 is a rear elevation of certain parts shown in Fig. 1.

Similar reference characters refer to similar parts throughout the different views of 50 the drawings.

The present invention will be hereinafter described with relation to its application to the Noiseless typewriting machine, although it is, of course, to be understood that it is 55 applicable to other forms of machines with-

out departing from the scope of the invention. In the Noiseless machine, which is of the double-shift style, the carriage has a transverse letter-space movement from right to left, and the present invention resides 60 more particularly in mechanism adapted to arrest the movement of the carriage to line-commencing position at a regularly indent-ed distance when it is desired to start a new paragraph. 65

Referring now to the drawings in detail, and more particularly to Fig. 1, 1 denotes the frame of the machine in which is mounted a fore and aft adjustable member 2, known as the "center tie mechanism," for 70 properly positioning a platen roller 3, mounted in a carriage 4, traveling on a shift rail 5, with respect to the end of the path of travel of the type. This carriage 4 carries at its rear line-lock stops, tabulat-ing stops and margin stops, but the latter, 6, need only to be shown and considered in this case. Co-acting with this stop 6 is a movable stop or margin release lever 7 which extends downwardly and fore and 75 aft of the machine beneath the carriage. This lever 7 is mounted in vertical trun-nions 8, which are carried by a horizontally disposed shaft 10, to permit universal move-ment. The shaft 10 has a forwardly ex-85 tendsing arm 11 which rests above a rear-wardly extending arm 12 of a key lever 13 pivotally mounted on a stud 14. It will thus be seen that as the key lever 13 is de-pressed the arm 11 is rocked upwardly 80 which will cause a rearward movement of 90 the margin release lever 7.

It will be noted that the coactive portion of the margin release lever 7 is forked as indicated at 16, and the margin stop 6, which 95 is longitudinally adjustable on its support, is provided with an extension 17, a portion of which is provided with suitable slots or a short rack in which a special or second stop 18 may be adjustably positioned, the stop 18 100 being shaped to clear the forked end 16 of the margin release lever 7 in both its normal and shifted positions. In other words, in normal operation the forked end of the mar-gin release lever does not engage the special 105 stop 18, but passes between its projections, as shown, so as to engage only the body por-tion of the stop 6.

Pivoted at 19 upon the center tie member 2, and at one side of the stop 6, is an aux-110

iliary or paragraphing lever 20, the upper end 21 of which normally stands clear of the margin release stop. The lower end of this lever is provided with a stud or pin 22 projecting to one side and into the path of travel of the margin release lever 7, as clearly shown in Fig. 3. The margin release lever 7 is also provided with a stud 23 adapted to laterally support the auxiliary lever 20 when the special stop 18 engages the same on the movement of the carriage to the right, the auxiliary lever 20 passing at that time under the pin and being supported thereby.

This device may be conveniently operated substantially as follows: The auxiliary lever 20 is inoperative except when it is desired to indent a paragraph, in which case the margin release key lever 13 is held down while the carriage is being returned to line-commencing position. This causes the margin release lever 7 to move rearward, as above described, but such rearward movement of the margin release lever causes the upper end 21 of the auxiliary lever to move forward into substantially the position previously occupied by the forked end 16, and, since this auxiliary lever is not forked, it will then engage the auxiliary stop 18, located on the body portion of the margin stop. The margin release key is held down until the end 21 of the auxiliary lever 20 has engaged this stop, whereupon it is released and the parts of the paragraphing mechanism return to normal position, and during the subsequent line movements of the carriage against the left margin, the end 16 of the margin release lever 7 will clear the special stop and engage only the main portion thereof in the usual manner.

Since the special stop 18 is adjustable on the body portion of the margin stop, it is clear that whatever this adjustment may be and also the adjustment of the stop with respect to the carriage, the special stop will always provide a uniform indentation of the paragraph to any desired amount.

From this description, it will be seen that the invention comprises a simple and practical paragraph key mechanism adapted to accomplish, among others, all of the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, in combination, a carriage, coöperable margin stops

therefor, means to release said stops, and auxiliary coöperable indenting stops for the carriage controlled by said means.

2. In a typewriting machine, in combination, a carriage, coöperable margin stops therefor, means to release said stops, and auxiliary coöperable indenting stops for the carriage controlled by said means, one of said indenting stops being relatively adjustable with respect to one of said margin stops. 75

3. In a typewriting machine, in combination, a carriage, coöperable margin stops therefor, one movable to clear the other, and normally inactive coöperable indenting stops for the carriage, one movable to engage the other and being actuated by said movable margin stop. 80

4. In a typewriting machine, in combination, a carriage, coöperable margin stops therefor, one movable to clear the other, and normally inactive coöperable indenting stops for the carriage, one movable to engage the other and being actuated by said movable margin stop and one of said indenting stops being relatively adjustable with respect to one of said margin stops. 85

5. In a typewriting machine, in combination, a carriage, a margin stop and an indenting stop movable therewith, and means on the machine frame movable relatively to 95 said stops out of the path of one and into the path of the other.

6. In a typewriting machine, in combination, a carriage, a margin stop and an indenting stop movable therewith, and means 100 on the machine frame movable relatively to said stops out of the path of said margin stop and into the path of said indenting stop.

7. In a typewriting machine, in combination, a carriage, a margin stop and an indenting stop movable therewith, and means on the machine frame movable out of the path of said margin stop and into the path of said indenting stop, said indenting stop 110 being adjustable relatively to said margin stop. 105

8. In a typewriting machine, in combination, a carriage, coöperable margin stops therefor, means to render said stops inactive, 115 and coöperable indenting stops for the carriage controlled by said means, one of said indenting stops being relatively adjustable with respect to one of said margin stops and one of said indenting stops and one of said margin stops being adjustable together with respect to the carriage. 120

9. In a typewriting machine, in combination, a carriage, an adjustable stop carried thereby having two effective portions adjustable relatively to each other, a margin release means coacting with one portion, and a paragraphing lever coacting with the other. 125

10. In a typewriting machine, in combina- 130

tion, a carriage, an adjustable stop carried thereby having two effective portions adjustable relatively to each other, a margin release lever coacting with one portion, and a 5 paragraphing lever coacting with the other and being actuated by said margin release lever.

11. In a typewriting machine, in combination, a carriage, an adjustable stop carried thereby having two effective portions, one of which is notched, a margin release lever having a forked end to pass the notched portion and coact with the other portion, and a paragraphing lever to be actuated by the 15 margin release lever to move into effective position.

12. In a typewriting machine, in combination, a carriage, an adjustable stop carried thereby having two effective portions, one of

which is notched, a margin release lever having a forked end to pass the notched portion and coact with the other portion, and means actuated by said margin release lever to be engaged by the notched portion of said stop. 20

13. In a typewriting machine, in combination, a carriage, a stop carried thereby having two effective portions, one of which is adjustable relatively to the other, and separate means coacting with two portions of said stop for controlling the margin and 25 paragraphing lines. 30

In testimony whereof I affix my signature, in the presence of two witnesses.
